MOISTURE EXTRACTION

Horace L. Smith, Jr., Richmond, Va., assignor to
Thermal Engineering Corporation, Richmond,
Va., a corporation of Virginia

Application July 17, 1934, Serial No. 735,718

3 Claims. (Cl. 34—48)

This invention relates to the extraction of moisture, and more particularly concerns improved apparatus for withdrawing moisture from cloth, fabrics or other materials which are permeable to air.

In many manufacturing processes, it is necessary to extract moisture from air permeable materials. Thus in the finishing of textiles, a web of textile fabric is subjected to one or more water rinsing operations prior to sizing or other treatment, and it is essential that the moisture absorbed by the fabric during rinsing be removed therefrom before the sizing or other treating material is applied. It has been customary to extract this moisture by continuously passing the wet material over a slot or similar opening in a chamber in which a vacuum is maintained by pumps or equivalent means, whereby the moisture in the fabric is entrained and withdrawn by 10 the air drawn therethrough into the vacuum chamber. This water withdrawn from the fabric contains a large amount of lint, threads, dye and other foreign material which is withdrawn from the vacuum chamber by the vacuum pump. 20 This foreign matter collects on the pump screens and stops the pumping action or, if no screens are used, clogs and injures the pumps and causes frequent shut-downs or breakage of apparatus.

It has been proposed to overcome the above explained difficulty by using steam jet ejectors for maintaining a vacuum within the vacuum moisture extracting chamber. Although the use of such ejectors avoids clogging difficulties to a certain extent, it is unsatisfactory in other respects. 30 Thus a large amount of steam is required to operate a steam ejector even under ordinary operating conditions, and the flow of extracted water into the ejector condenses some of the steam therein before it has performed its ejection function, thereby greatly increasing the steam consumption of the ejector. Further, since the water passing through the ejector is contaminated with lint, dye and other foreign matter extracted from the fabric, the hot water condensed from the ejector exhaust is unfit for most uses and is accordingly wasted.

With the above and other considerations in mind, it is proposed in accordance with the present invention to provide improved apparatus for extracting moisture from air permeable materials such as cloth or other fabric, which apparatus, while effectively removing the moisture, entirely avoids the clogging of screens or pumps by foreign matter in the extracted moisture, the lowering of ejector efficiency by the condensation

of steam in the ejector and the contamination of the ejector condensate by the foreign matter.

Another object of the invention is the provision of an improved type of vacuum chamber for use with moisture extracting apparatus of the type described.

In general, the above and other objects of my invention are carried out by providing moisture extraction apparatus including a vacuum chamber into which the air and entrained water are drawn from the fabric or other moist permeable material under treatment, and by providing means for continuously removing from this chamber the extracted water and the foreign matter carried thereby without passing this water through the exhausting pump or other vacuum producing means.

In a preferred form of my invention, this is accomplished by connecting the pump or other vacuum producing means to a point above the bottom of the vacuum chamber and by providing an extracted water outlet means comprising a downwardly extending duct of considerable length connected at its upper end to a point at or adjacent the bottom of the vacuum chamber and having an air seal or trap at its lower end. With this arrangement, the water or other liquid extracted from the material under treatment, together with the foreign matter carried thereby, continuously flows off by gravity through the outlet duct, and the water seal provided by this water at the lower end of this duct prevents the egress of air through the duct to the vacuum chamber. The pump or other means for maintaining a vacuum in the chamber withdraws the entraining air only from this chamber and accordingly, the invention entirely prevents the condensation of steam and contamination of condensate in an ejector type of exhauster, as well as the clogging of a pump exhauster.

In a modified form of the invention, the vacuum chamber is provided with a combined water and air outlet opening so shaped as to aid in separating the extracted moisture from the entraining air as these fluids leave the chamber. In a further modification of the invention, the moisture extracting or inlet opening of the vacuum chamber is so arranged as to prevent the distortion of this inlet by the vacuum maintained within the chamber.

The invention will be best understood by reference to the accompanying drawings, in which certain embodiments thereof have been disclosed. In the drawings;

Figure 1 is a diagrammatic representation of a

fabric treatment to which the moisture extraction apparatus of the present invention is applicable;

5 Figure 2 is an elevation, partly in section, of the moisture extraction apparatus embodying the invention;

Figure 3 is a plan view, partly in section, of the apparatus shown in Figure 2;

10 Figure 4 is a plan view, similar to Figure 3, showing a modified form of apparatus embodying the invention;

15 Figure 5 is a sectional elevation of a modified form of moisture extracting apparatus embodying the invention, the section being taken along the line 5—5 of Figure 6; and

Figure 6 is a plan view of the apparatus shown in Figure 5 disclosing my improved vacuum chamber inlet slot construction.

20 The moisture extraction apparatus of the invention may be used wherever it is desired to withdraw moisture from air permeable material. One important application of this apparatus is in the finishing of woven textile materials. It is customary to thoroughly rinse certain textile 25 fabrics with water prior to the application of starch or sizing thereto or other treatment thereof, and it is usually essential that the rinse water be removed before the fabric is subjected to further treatment. In one fabric treating process 30 as illustrated in Figure 1, a continuous web 5 of textile fabric is moved between rinse water sprays 6 which thoroughly saturate the fabric, after which the web passes over a guide roll 7 and over a stationary moisture extracting cylinder or 35 vacuum chamber 8. The chamber 8 is provided with a very narrow slot 9 along the upper cylindrical surface thereof, this slot being substantially coextensive with the width of the fabric web, as shown in Figures 2, 3 and 4. A vacuum is maintained within the chamber 8 by means herein- 40 after described, and air is accordingly drawn through the fabric as it passes over the slot 9 with the result that the water carried by the fabric is entrained in the air and drawn out of 45 the fabric into the chamber 8. The fabric web 5 then passes through a sizing bath 10 under a suitable roll 11 and is delivered to drying or other treatment means, not shown, over the guide roll 12.

50 The apparatus of the present invention acts to maintain the desired vacuum in the chamber 8 by continuously removing the entraining air and the extracted water from this chamber. The vacuum creating means may comprise a vacuum pump, a steam ejector or any other device capable of continuously withdrawing air from the chamber 8 at a suitably high rate of flow. In the embodiment of the invention shown in Figure 2, a steam jet ejector, generally designated J, is employed for maintaining a vacuum in the chamber 8. This form of evacuating means is particularly adaptable in many textile finishing plants where heated water is employed in various treating processes, since the hot water recovered from the ejector may be usefully employed in such plants.

70 The ejector J may be of known construction and as shown comprises a steam nozzle 13 located in a chamber 14 and disposed to direct a high velocity steam jet axially through a contracted throat or Venturi tube 15. In accordance with the invention, the suction pipe 16 of the ejector is connected to the vacuum chamber 8 at or adjacent the top thereof, and as shown in Figure 2, this 75 pipe is connected to the upper surface of the

chamber 8 adjacent one end of the chamber and communicates with the chamber 14 of the ejector adjacent the nozzle 13. Steam is supplied to the ejector nozzle 13 from a suitable source through the pipe 17.

5 The outlet or exhaust pipe 18 of the ejector J is connected to suitable condensing means illustrated at C. The condenser may take any suitable form and as shown comprises a chamber 19 communicating with the ejector exhaust pipe 18 through an inlet opening 20 at its upper surface adjacent one end thereof, and a condensate outlet 21 in its lower surface adjacent its opposite end. Cooling water is sprayed into the inlet end of the chamber 19 through a pipe 22 and small auxiliary 15 water sprays 23 are provided at spaced points along the center of the chamber. An air outlet opening 24 is provided at the outlet end of the condenser chamber as shown. In operation, the air and steam delivered by the ejector exhaust 18 passes through the condenser chamber 19, the steam is condensed by the water sprays and the mixed condensate and spray water flow off through the outlet 21, the air passing out through the opening 24.

25 By properly designing the condenser, the water recovered therefrom may be delivered at a comparatively high temperature and usefully employed in various processes such as those incident to the finishing and manufacture of fabrics.

30 As explained above, the water extracted from the fabric web 5 is contaminated with lint, threads, dye and other foreign matter. If this contaminated water passed through the ejector J, the hot water recovered from the ejector exhaust would be unfit for use in most manufacturing operations. Further, if the comparatively cold water extracted from the fabric passed into the ejector chamber 14, it would come into direct contact with and condense some of the steam in 35 the jet from the nozzle 13 before this steam could perform its propelling function in the throat 15. In accordance with the present invention, the water extracted from the fabric is separated from the entraining air in the vacuum chamber 8 and 40 is continuously removed from this chamber without passing through the exhausting mechanism and without either breaking the vacuum in the chamber or employing pumps or equivalent propelling means.

50 In order to remove the contaminated extracted water, I provide a liquid column in a vertically extending duct 25 connected at its upper end to a point adjacent the bottom of the vacuum chamber 8, and having a liquid seal or trap at its lower end. The liquid seal or trap may comprise a reverse bend at the lower end of the duct 25, the upwardly extending leg of the duct being shorter than the downwardly extending leg thereof as shown. The outlet of the duct may be connected to a sewer or other waste water receiver.

55 In the operation of the apparatus described, the water saturated fabric web 5 passes over the slot 9 in the vacuum chamber 8 and the vacuum created within the chamber 8 by the ejector J causes air to flow at a high velocity through a limited area of the fabric thereby entraining and extracting water therefrom. The slot 9 is very narrow, in practice it may be from .005 to .064 inches wide. Accordingly, although the velocity 60 of the air and entrained water through the slot itself is very high, this velocity immediately drops to a much lower value as the air and water enter the chamber 8. At this point, the extracted water falls to the bottom of the chamber 8 and 65 70 75

flows off by gravity to the duct 25 while the entraining air is drawn off through the ejector as explained above. The duct 25 is so designed as to vertical extent and cross section that the water column built up therein by the vacuum in the chamber 8 is capable of balancing the highest vacuum which the ejector apparatus can establish in the vacuum chamber. Thus the water outlet duct is always sealed, and at the same time permits the continuous flow of extracted contaminated water from the chamber 8.

As explained above, pumps or other mechanical exhausting means may be used on my improved moisture extracting apparatus. This embodiment is disclosed in Figure 4 wherein an exhaust or vacuum pump, conventionally represented at P, is connected through a duct 16' with the upper surface of the vacuum chamber 8'. The chamber 8' is provided with a trapped water column outlet duct 25' which may be identical with the duct 25 of Figure 2. With this arrangement, the contaminated water separates by gravity from the entraining air in the vacuum chamber 8' and flows off through the duct 25', and the clogging or injury of the pump P by the lint and other foreign matter in the extracted water is effectively avoided.

In a modified form of the invention, as shown in Figure 5, the vacuum chamber 27 is provided with a single outlet 28 at one end thereof through which both the entraining air and the extracted moisture pass, and which is so shaped as to aid in separating the moisture from the air at this point. Thus the outlet end of the vacuum chamber 27 communicates directly with the downwardly extending water outlet pipe or duct 29 and the upper surface of the chamber outlet duct 28 is curved downwardly as shown at 30 toward the upper end of the pipe 29. Just beyond this downward curve, the duct 31 leading to the evacuator is joined to the vacuum chamber outlet duct 28 and the water outlet 29, the arrangement being such that in entering the air duct 31, the air makes a U-bend and substantially reverses its direction of flow. With this arrangement, as the stream of air and water flows out of the vacuum chamber 27 through the duct 28, this stream is deflected downwardly toward the water outlet pipe 29 and the water in the mixture, being considerably heavier than the air, continues to flow downwardly into the pipe 29 while the lighter air passes upwardly around an acute angle bend into the air duct 31 to the evacuator. It is, of course, to be understood that a steam jet ejector, vacuum pump or other type of evacuator is connected to the air duct 31.

A modified form of water seal for the water outlet duct is disclosed in connection with the apparatus shown in Figure 5. This seal comprises a large tank or other receptacle 32 in which the lower end of the pipe 29 is submerged. The capacity of the tank 32 is such that when it is filled to the level of its overflow pipe 33 and the evacuator is started, the column of water drawn up in the pipe 29 will not empty the tank 32 to a point where the lower end of the pipe 29 is uncovered. In other words, the tank 32 has a greater volumetric capacity than the pipe 29 or at least a greater capacity than that portion of the pipe 29 which is filled with water when the evacuator is in operation. With this arrangement, when the moisture extracting apparatus is started up after an idle period, the water seal in the pipe 29 is not broken and the required vacuum is quickly built up in the chamber 27 regardless of the rate

of flow of extracted liquid into the upper end of the pipe 29. The water seal disclosed in Figure 5 is, of course, applicable to all modifications of my improved moisture extracting apparatus.

Another feature which is applicable to all forms of apparatus embodying my invention is an improved inlet opening for the vacuum chamber which is illustrated in Figure 6. In order that the entraining air shall pass through the web 5 at a very high velocity and thus extract substantially all of the moisture therefrom, it is desirable that the slot be extremely narrow and that a high degree of vacuum be maintained in the chamber 27. With the apparatus designed to handle a web 5 of considerable width, there is some danger that the vacuum chamber may collapse due to the vacuum therein to such an extent that the inlet slot or portions thereof are contracted or closed, thus interfering with the moisture extracting operation. It is difficult and expensive to brace or reinforce a continuous slot without placing obstructions in the path of the air and entrained water drawn therethrough. In accordance with one feature of my invention, I overcome the above noted difficulties by forming a plurality of comparatively short slots 34 in the surface of the vacuum chamber 27, these slots being disposed with their ends in overlapping relationship, as shown in Figure 6, and being closely spaced so that the web 5 extends over all of these slots. I prefer to arrange the slots 34 as shown in substantially parallel relationship and at a slight angle to the axis of the vacuum chamber. With this arrangement, a bridge of metal, indicated at 35, extends between the ends of the adjacent slots and prevents the closing of the slots due to the collapse of the vacuum chamber. The individual slots may be of any desired length short of that at which there is danger of restriction or closing thereof and any desired width of web may be handled by increasing the number of overlapping slots employed. Since the ends of the adjacent slots 34 overlap transversely of the web, moisture is extracted from the web across its entire width.

Although the invention has been described in connection with certain forms of apparatus employed in the extraction of water from textile fabrics, it should be understood that the invention is generally applicable to any operation in which water or moisture are extracted by the suction of air through the material under treatment, and that various changes and omissions may be made in the apparatus used without departing from the scope of the invention as defined in the appended claims.

I claim:

1. Apparatus for extracting moisture from permeable material comprising a vacuum chamber having a restricted inlet opening therein, means for continuously moving moist air permeable material over said opening, a steam jet ejector having an inlet duct connected to said chamber adjacent its upper surface, means for condensing steam from said ejector and a downwardly extending water outlet duct having its upper end in communication with said chamber adjacent the lower surface of said chamber and having a reverse bend adjacent its lower end.

2. Apparatus for extracting moisture from permeable material comprising a vacuum chamber having a restricted inlet opening therein, means for continuously moving moist air permeable material over said opening, a steam jet ejector having an inlet duct connected to said chamber ad-

5 jacent its upper surface, means for condensing steam from said ejector, a downwardly extending water outlet duct having its upper end in communication with said chamber adjacent the lower surface of said chamber, and a water seal at the lower end of said duct.

10 3. Apparatus for extracting moisture from permeable material comprising a vacuum chamber having a restricted inlet opening therein, means for continuously moving moist air permeable material over said opening, a steam jet ejector hav-

5 ing an inlet duct connected to said chamber adjacent its upper surface, means for condensing steam from said ejector, a downwardly extending water outlet duct having its upper end in communication with said chamber adjacent the lower surface of said chamber and a receptacle surrounding the lower end of said duct and having a volume above the lower end of said duct at least equal to the volume of liquid carried by said duct.

10
